(57) **CLAIM**

(21) Appl. No.: **29/237,716**

The ornamental design for an over-the-tank toilet tissue
reserve, as shown and described.

(22) Filed: **Sep. 6, 2005**

DESCRIPTION

(51) **LOC (8) Cl.** 20-02

FIG. 1 is a front elevational view of an over-the-tank toilet
tissue reserve showing our new design;

(52) **U.S. Cl.** **D6/520**

FIG. 2 is a side elevational view thereof;

(58) **Field of Classification Search** D6/515-523;

FIG. 3 is a top plan view thereof;

D3/201, 304; 206/389, 391; 211/13.1, 86.01,

FIG. 4 is a perspective view thereof; and,

211/71.01, 181.1; 242/580; 248/309.1

FIG. 5 is a bottom plan view thereof.

See application file for complete search history.

The broken-line disclosure of elements in the views is for
illustrative purposes only and forms no part of the claimed
design.
